UNITED STATES PATENT OFFICE

ELLIOTT E. ANTHONY, OF CHICAGO, ILLINOIS

POWER CONVERTING DEVICE

Application filed February 20, 1929. Serial No. 341,378.

This invention relates to power converting devices and it has for its principal object to produce an attachment, tool or device for application to a rotary power device so as to utilize the same for actuating reciprocatory implements in drilling, riveting, chiseling, chipping, stamping and the like.

In certain industries rotary drills and other devices or tools of the rotary type are more extensively used, but at times it is desirable or necessary to employ devices of the reciprocatory type, for which latter devices, of course, complete extra equipment must ordinarily be provided. A further object of the invention, therefore, is to obviate the necessity for such full extra equipment and thereby minimize expense by providing a simple and inexpensive, yet practical and durable, supplemental tool or attachment which, in use, may be applied to an ordinary rotary drill or other power device for converting its motion to actuate a reciprocatory tool.

Other objects and advantages to be attained will more fully appear in the following description:

In the accompanying drawings illustrating a practical adaptation of the invention,—

Fig. 1 is a side elevation of the device with an ordinary reciprocating drill bit applied thereto;

Fig. 2 is a longitudinal section of the device on an enlarged scale;

Fig. 3 is a fragmentary longitudinal section on the line 3—3 of Fig. 1;

Fig. 4 is a cross section on the line 4—4 of Fig. 2;

Fig. 5 is a section on the line 5—5 of Fig. 2;

Fig. 6 is a section on the line 6—6 of Fig. 2; and

Fig. 7 is a fragmentary view, in side elevation, of the end portion of the reciprocating inner tube which carries the hammer element of the device, to illustrate the arrangement of the actuating cam thereof.

Referring now to the drawings, the numeral 10 designates the tubular main body portion of the device. Fitted loosely within one end portion of the tubular casing 10 is a tool holder or anvil 11 having an axial socket 12 for the reception of the shank 13

of a tool 14, which latter, as shown in the drawings, is an ordinary reciprocating drill bit, but, obviously, may be a tool or member of other character, such as a chisel, stamping tool, riveting element, or the like.

The member 11 has a restricted longitudinal as well as rotatable movement in the tubular casing 10. This is conveniently accomplished, as shown in the drawings, by reducing the middle portion of said member 11 in diameter, and thereby providing end flanges or collars 15, 16, respectively, which latter cooperate with a stop element 17 secured to the tubular casing 10 by screws 18. The stop element 17 is preferably semi-cylindrical, as shown, its peripheral face being conformed to and fitted snugly against the inner face of the tubular casing 10. This element 17 is further provided with a bore 19 preferably somewhat larger in diameter than the reduced middle portion of the tool holder or anvil 11, and one side of said element 17 is slotted as at 20 to accommodate a segmental block 21 which is secured by the screw 22 to the reduced middle portion of said member 11, said block being considerably narrower than the width of the slot 20 in the element 17. By the provision of the element 17, which latter is of a longitudinal dimension considerably less than the distance between the end flanges or collars 15 and 16 of the tool holder or anvil 11, and the block 21 being narrower than the slot 20 in said element 17, the member 11 is retained within the tubular casing 10 but is permitted limited endwise and rotative movement.

Slidable longitudinally within the tubular casing 10 is an inner tube 23, in one end of which, adjacent to the tool holder or anvil 11, is a hammer element 24. The hammer element 24 is generally cylindrical in form and fitted tightly within the tube 23 and secured in place by a transverse pin 25, said member 24 preferably having an enlarged head portion 26 affording an annular shoulder 27 for engaging the end of the tube 23. In order to prevent rotation, yet permit endwise reciprocation of said inner tube 23 with in the outer tube 10, a longitudinal slot 28 is

provided in said inner tube, with which slot a screw-stud 29 on the tube 10 cooperates.

In the end portion of the inner tube 23 opposite to that in which the hammer element 24 is secured, is provided a mutilated screw thread or spiral cam track 30 with which cooperates a corresponding mutilated screw thread or spiral cam portion 31 on the enlarged portion or head 32 of a spindle 33, which latter is insertable in the chuck of a rotary drill or the like, or it may be connected in any obvious manner with any rotatable power element.

The spindle portion 33 is rotatably mounted in a head 34 preferably detachably secured within adjacent end portion of the outer tube 10 as by the screws 35. In order to afford sufficient bearing for said spindle in said head 34, the latter is provided with a central extension 36 with the outer end of which cooperates a thrust collar 37 secured by the said screw 38 to the spindle. Opposed to the thrust collar 37 is the shoulder afforded by the enlargement 32 of the spindle which abuts a boss 39 on the inner end of the head 34. By this arrangement the spiral cam or screw thread 31 rotates in fixed longitudinal relation to the tubular casing 10 and in cooperative relation to the cam or screw thread 30 on the inner tube 23, and, obviously, said sleeve 23 is caused to move towards the head 34.

Within the inner tube 23 and interposed between the inner ends of the hammer element 24 and the enlarged portion or head 32 of said spindle 33 is a coil spring 40, said spring being under compression and tending to move said inner tube towards the end of the outer tube 10 in which the tool holder or anvil 11 is mounted. Normally, the spring 40 yieldably holds the hammer element 24 in contact with the tool holder or anvil 11, as shown in Figs. 2 and 3 of the drawings, and to permit the spindle 33 to rotate freely without interference to itself or to the action of the spring 40, the latter has its end portion 41 turned inward and extended axially so as to seat in an axial cavity 42 in the inner end of the enlargement 32 of said spindle 33.

In the operation of the device, the spindle 33 rotating in one direction, right-handed according to the arrangement of the cooperating spiral cams or mutilated screws 30 and 31, as shown, the inner tube 23 is intermittently moved towards the head 34 and at a speed corresponding, of course, to that at which the spindle rotates. At the instant the mutilated portions of the two spiral cams or screws 30 and 31 meet or register, the spring 40 which has been placed under compression in excess of that under which it is normally set reacts to snap or suddenly move said inner tube 23 in the reverse direction and thereby drives the hammer element 24 in forcible contact with the tool holder or anvil 11,

which latter has been depressed by the operator against the normal tension of the spring 40 and within the limits of the play afforded by the clearance between the stop element 17 and the end collars 15 and 16 of said tool holder or anvil 11.

In order to permit freedom of movement to the unitary reciprocating piston of the device, including the inner tube 23 and the hammer element 24, the latter, which would otherwise completely close the end of the tube 23, is provided with a longitudinal passageway 43 or a plurality thereof, as may be desired. As shown in the drawings, a single passageway 43 is bored axially through the hammer element 24, but, obviously, in cases where a plurality of said passageways are provided they may be either bored through the body at points between the center and periphery thereof, or said hammer element may be provided with longitudinal peripheral grooves. The opposite end of the tube 23 is vented by providing considerable clearance in the opening 44 in which the head or enlargement 32 of the spindle 33 works. This venting of the reciprocating piston overcomes the resistance of air compression and evacuation at the opposite ends thereof and permits it to slide freely and rapidly, which is essential to the proper actuation of a device of this character.

Obviously, the device may be considerably modified and applied to many different uses without in the least departing from the spirit and scope of the invention as defined by the appended claims. The invention, therefore, is not limited to the specific construction and arrangement shown in the accompanying drawings.

What I claim as new and desire to secure by Letters Patent is:

1. In a device of the character described, a tubular body casing, an element constituting an anvil and tool holder supported in the end portion of said tubular casing and having limited endwise movement, a spring-pressed impact element mounted to reciprocate longitudinally in said tubular casing and normally in contact with said anvil and tool holder element, and an axially rotatable power element in said tubular casing, said power element having a spiral cam and said impact element having a cooperating portion for engagement with said cam whereby said impact element is positively moved in one direction, said impact element moving in the opposite direction by the reaction of its spring upon its disengagement from said cam.

2. In a device of the character described, a tubular body, a longitudinal reciprocating piston in said tubular body, said piston comprising a tube, a hammer element secured in one end of the tube, and a mutilated spiral cam secured in the opposite end of said tube and having an axial bore, a spindle rotatable

axially in said tubular body but being held from endwise movement therein, said spindle extending through the axial bore of said spiral cam and having a mutilated spiral cam at its inner end in cooperative relation to the cam on said tube of the reciprocating piston whereby to move the latter in one direction, a spring located in said piston tube and being normally under compression with one end 10 engaging the adjacent inner end portions of said hammer element and its opposite end engaging said spindle axially, and a combined anvil and tool holder element mounted in the adjacent end portion of said tubular body 15 with limited endwise movement and being normally engaged by said hammer element.

3. In a device of the character described, a tubular body, an element constituting a combined anvil and tool holder mounted in one end of said tubular body and having limited endwise and rotative movement therein, a reciprocating tubular piston in said tubular body, a hammer element secured in one end of said piston tube and normally 20 in contact with said tool holder, said piston tube having an internal mutilated spiral cam at its opposite end provided with an axial bore, a rotatable power spindle mounted axially in said tubular body and extending 25 through the axial bore in said spiral cam, a mutilated spiral cam on said power spindle in cooperative relation to said cam on said piston tube, a coil spring located in said piston tube with one end bearing on said ham- 30 mer element and its opposite end engaging the inner end of said power spindle axially with respect thereto, and means for permitting longitudinal movement of said piston tube and at the same time holding it from 35 rotation in said tubular body.

4. In a device of the character described, a tubular body, a removable head in one end of said tubular body having an axial bore, a power spindle mounted rotatably in the bore of said removable head but being held against endwise movement therein, a combined anvil and tool holder element mounted in the opposite end of said tubular body and having restricted longitudinal 45 movement, a piston comprising a tube slide- able longitudinally but being nonrotative in said tubular body, a hammer element fitted in one end of said piston tube in cooperative relation to said anvil element, a fixed axially bored spiral cam in the opposite end of said piston tube, a cooperating spiral cam located in said piston tube and being fixed on the inner end portion of said power spindle which is extended through the axial bore of 50 said first mentioned spiral cam, and an inter- posed spring element normally under compres- sion with one end bearing against said hammer element, and its opposite end engag- 55 ing the inner end of said power spindle axially.

5. In a device of the character described, a tubular body, a reciprocating piston in said tubular body, said piston having a hammer element at one end, means for reciprocating said piston longitudinally in said tubular 70 body, said means including a cam device for moving it in one direction and a spring for moving it in the opposite direction, an anvil mounted in the end portion of said tubular body, said anvil having an axial tool receiv- 75 ing socket and being provided with a circum- feren- tial groove, means for supporting said anvil element with restricted longitudinal movement and at the same time preventing rotation of said anvil element, the same com- 80 prising a circular stop element having a slot in one side thereof whereby to straddle the intermediate portion of said anvil element, means for detachably securing said stop ele- 85 ment in said tubular body, and a segmental block fitted loosely in the slotted portion of said stop element and being detachably se- cured to the intermediate portion of said anvil element.

In testimony whereof I have signed my name to this specification.

ELLIOTT E. ANTHONY.
